(57) **CLAIM**

We claim a new ornamental design for a lid for a bottle, as shown and described.

DESCRIPTION

FIG. 1 is a perspective view of a lid for a bottle according to our new design;

FIG. 2 is a second perspective view of the lid for a bottle of FIG. 1;

FIG. 3 is a front elevational view of the lid for a bottle of FIG. 1;

FIG. 4 is a rear elevational view of the lid for bottle of FIG. 1;

FIG. 5 is a top plan view of the lid for a bottle of FIG. 1;

FIG. 6 is a bottom plan view of the lid for a bottle of FIG. 1;

FIG. 7 is a right side elevational view of the lid for a bottle of FIG. 1; and,

FIG. 8 is a left side elevational view of the lid for a bottle of FIG. 1.

The broken lines in FIGS. 1 and 6 represent environment and are for illustrative purposes only and do not constitute part of the claimed design.
